UNITED STATES PATENT OFFICE.

JAMES C. DORAN AND JAMES A. DORAN, OF PROVIDENCE, RHODE ISLAND.

BUTTON.

No. 873,354.

Specification of Letters Patent.

Patented Dec. 10, 1907.

Application filed May 3, 1906. Serial No. 314,967.

To all whom it may concern:

Be it known that we, JAMES C. DORAN and JAMES A. DORAN, both citizens of the United States, and both residing at Providence, in the county of Providence and State of Rhode Island, have invented certain new and useful Improvements in Buttons, of which the following is a specification, reference being had therein to the accompanying drawing.

10

Our invention relates to improvements in buttons of all kinds, and has for its object a construction which shall comprise a minimum of parts, be free of solder, and possess 15 a maximum of strength and durability.

To these ends essentially our invention consists in the novel construction of the back plate with an eye integral therewith.

In the drawings which constitute a part of 20 this specification, Figures 1 and 2 are plan and central sections respectively of a button back blank. Figs. 3 and 4, like views respectively of the blank after the cupping operation. Figs. 5 and 6, similar views respectively of the blank after the swaging of the cup and the piercing operation. Fig. 7, a side elevation of the completed back plate member. Fig. 8, a perspective view of the completed button, and Fig. 9, a central transverse section of the same on line $x-x$ of Fig. 8.

Like reference characters indicate like parts throughout the views.

The button back comprises a back plate 35 and an integral shank composed therefrom, said shank having a hollow base and a compressed solid adjacent portion having an opening, and a face plate with its marginal edge folded inwardly and downwardly over the 40 edge of the back plate and firmly clamped thereto, all as more fully now to be described.

In constructing our novel button, a blank piece of metal or other material, A, having a 45 capacity for bending, is cut in a circular or other outline to conform with the ultimate shape of the button, as shown in Fig. 1. By a plunger or other tool, the central portion of the blank, A, is cupped up as at B, in Fig. 50 4. The sides of the cup are then by swaging

dies or otherwise compressed or forced into contact with each other, forming a flattened post or shank, as shown at B in Fig. 6, which is practically solid. The post is transversely perforated as at b in Fig. 6. The 55 margins of the opening or eye, b, are rounded to prevent any edges for the thread to wear upon when the button is secured to the garment.

The face plate, C, of the button may be of any desired construction or material, and may be applied to the back plate in any manner. We prefer, however, to engage the parts by folding the margin of the front plate, C, inwardly and downwardly upon the rear 60 face of the back plate, A, thereby avoiding the use of solder here as was done in the formation of the eye shank, B, upon the back plate. It will be noted that by this construction is avoided the weakening effect 65 upon the back plate and eye shank of the annealing operation involved in soldering these two parts together; also, that the avoidance of radial prongs upon the shank for engaging purposes insures against withdrawal of the 70 shank, from the back plate under excessive strain.

What we claim is,

1. A button back comprising a back plate and a shank integral therewith, said shank 80 having a hollow base and a solid adjacent portion provided with an eye opening therethrough.

2. A button back comprising a back plate having a shank integral therewith, said shank 85 comprising a hollow substantially conical base and a flat upper portion provided with a transverse perforation.

3. A button back comprising a back plate and a shank integral therewith, said shank 90 having a hollow base and a solid adjacent portion provided with a transverse perforation having a rounded margin.

4. A button back comprising a back plate and a shank integral therewith and compressed therefrom, said shank having a hollow base and a compressed solid adjacent portion with an opening therein.

5. As an improved article of manufacture, a button composed of a back comprising a 100

back plate with integral shank, said shank having a hollow substantially conical base and a compressed flattened solid adjacent portion provided with an opening, and a face plate having its marginal edge folded inwardly and downwardly over the edge of the back plate and fixedly clamped thereon.

In testimony whereof we have affixed our signatures in presence of two witnesses.

JAMES C. DORAN.

JAMES A. DORAN.
